APPARATUS FOR TREATING PETROLEUM

Kearney F. Mitchell, Jennings, La.

Application June 5, 1953, Serial No. 359,820

1 Claim. (Cl. 196--106)

My invention relates to apparatus for treating petroleum.

It relates particularly to treating petroleum by distillation in such manner that all component fractions remain undisturbed in their natural molecular arrangements and composition, and with a separation of the products contained in the petroleum into yields of any desired specific gravity.

A prime object of this invention is to effect distillation to any desired range without subjecting any desired gravity to any more heat than the amount of heat required to vaporize any and all gravities of the different cuts obtained, thereby eliminating any vapors that are formed when oil is subjected to a greater amount of temperature than is required to vaporize each successive gravity as it is separated, thereby keeping recovery yields to a maximum. The treatment of any oil either by distillation or cracking may be effectually practiced by this invention.

Another object is to provide economy in operation by the use of several heat exchanges. The total charge of petroleum or cracking stock as it is processed in this invention does not have to be subjected to any more heat than is required to vaporize each of the different gravities or cuts, thereby keeping operating fuel consumption to a minimum.

The said objects I have accomplished by the means now to be described in detail and claimed, it being understood that changes in the precise embodiment of invention herein disclosed can be made within the scope of what is claimed without departing from the spirit of the invention.

The novel features which I believe to be characteristic of this invention are set forth with particularity in the appended claim. The invention itself, however, both as to organization and operation, together with additional objects and advantages thereof, will be best understood from the following description of a specific embodiment when read in connection with the accompanying drawing in which,

Fig. 1 is a view partly in section of the left portion of the apparatus.

Fig. 2 is an elevational view on a reduced scale of the entire apparatus.

Referring to the drawing, a pipe 4 is connected for delivering oil into the bottom of a tank 5 in which it rises around a heat exchange coil 5'. From the top of the tank 5, the oil passes through a pipe 6 and into the bottom of a tank 7 where it rises around three heat exchanger coils which will be referred to later. From the top of the tank 7, the oil passes through a pipe 8 into the bottom of a distillation tower 9 and rises to about the level L around a cone shaped member 10 of a stack which has an exhaust flue 11. The member 10 is attached to the periphery of the bottom of the tower 9. During the passage of oil upwardly in the tower 9, it is subjected to heat generated inside of the member 10 the bottom of which contains a burner 12 supplied with combustible fuel through a pipe 13 controlled by a valve 14. Passages 14' supply outside

2

air to the burner 12. Vapors pass out from the top of the tower 9 through a pipe 15 which contains a pressure regulator 16 and then pass out through the heat exchanger coil 5' which is inside the tank 5.

5 A stabilizer receptacle 18 is placed around the intermediate portion of the stack. From the receptacle 18, oil passes out through a pipe 19. This pipe leads from the receptacle 18 between the top and bottom thereof. A control device 20 for maintaining the level L is connected 10 with the pipe 19 through a control valve 21. The upper end of the control device 20 is connected with the tower 9 by a pipe 22. A sight glass 23 is connected to the control device 20.

The pipe 19 as shown in Fig. 2 is connected to the bottom of a chamber 24 which encloses a heat exchanger. After rising around this heat exchanger, the oil goes through a pipe 25 into the bottom of a second tower 26 which is equipped like the first tower 9. From the tower 26 a pipe 27 leads into the bottom of a chamber 28 which is like the chamber 24. From the upper end of the chamber 28, a pipe 29 leads into the bottom of a third tower 30 which is like the towers 9 and 26. From the tower 30, a pipe 31 leads into the bottom of a chamber 32 which is like the chambers 24 and 28. From the chamber 32, 20 a pipe 33 leads into the bottom of a fourth tower 34 which is like the other towers except that it is provided with an outlet 35. From the top of the tower 34, a pipe 36 leads into the top of a heat exchanger coil in the chamber 32. The lower end of this coil is connected to a pipe 37 which leads into the bottom of a heat exchanger coil 38 in the tank 7 as shown in Fig. 1 and has an upper outlet end. From the top of the tower 30, a pipe 39 leads into the top of a heat exchanger coil in the chamber 28. The lower end of this coil is connected to a pipe 40 which leads into the bottom of a heat exchanger coil 41 in the tank 7 and has an upper outlet end. From the top of the tower 16, a pipe 42 leads into the top of a heat exchanger coil in the chamber 24. The lower end of this coil is connected to a pipe 43 which leads into the bottom of a heat exchanger coil 44 in the tank 7 and has an upper outlet end.

The operation and advantages of this invention will be apparent in connection with the foregoing description and the accompanying drawing and to a certain extent have 45 already been stated. The gases of combustion pass out through the stacks or flues 11 of the towers. Oil is admitted to the apparatus by the supply pipe 4 in any suitable manner such as by a charge pump. The oil first passes upwardly in the tank 5 around the heat exchanger coil 5' which consists of a single coil extending spirally downward. The oil traveling upwardly is partly pre-heated in the tank 5 by the coil 5' which takes the hot vapors from the top of the first tower 9 delivered through the pipe 15. The oil then passes from the top of the tank 5 through the pipe 6 which is connected to the bottom of the tank 7 and rises around the three coils 38, 41 and 44. The oil then passes through the pipe 8 into the bottom of the tower 9, having been previously heated by passing around heat exchanger coils. Oil entering the tower 9 is further heated by means of the burner 12 to whatever temperature is necessary to vaporize whatever part of the oil is desired as being the light ends or first cut of the oil extracted. These vapors then pass from the top of the tower 9 into the pipe 15 which has a pressure regulator 16, and then travel through the coil 5'. The lowest heat is first employed in acting on the oil. The resulting products therefrom are led off through the pipe 19 after having passed the level regulator 20.

Each tower has a stabilizer receptacle 18 attached outside the stack 11 near the upper portion of the tapered member 10, the upper end of the receptacle being below the oil level L in the tower. The oil thus heated has a

tendency to rise and upon reaching the upper open end of the stabilizer 18 falls into it and flows from the tower through the pipe 19 which is connected to the side of the stabilizer. As the oil travels from one tower to another, vaporization is effected. Since the heat increases in each tower, it is apparent that the quantity of oil decreases from one tower to another until total vaporization is effected. Since in each tower a different product is obtained by the increase of temperature, any desired amount of products may be extracted by increasing or decreasing the number of towers which are in operation. The pressure in successive towers has been found to be five to ten pounds less than the pressure in the preceding tower.

I claim:

Apparatus for treating petroleum consisting of a series of distillation towers, a stack attached to the bottom of each of said towers and extending up through the center thereof, a burner in the bottom of each stack, a tank, a heat exchanger coil in said tank, a pipe for delivering oil into the bottom of said tank around said coil, a pipe connecting the top of the first tower with the top of said coil, a second tank, several heat exchanger coils in said second tank, a pipe connecting the top of the first tank to the bottom of said second tank in which oil rises around said heat exchanger coils, a pipe connecting the top of said second tank with the bottom of the first tower, a stabilizer

5
10

receptacle around an intermediate portion of each of said stacks, chambers positioned in succession between said distillation towers, a heat exchanger coil in each of said chambers, pipes in succession connecting the stabilizer receptacles with the bottoms of said chambers, pipes in succession connecting the tops of said distillation towers with the tops of the coils in said chambers, pipes in succession connecting the bottoms of said coils individually with the bottoms of the several coils in the second tank, and means for maintaining the level of oil in said towers.
